UNITED STATES PATENT OFFICE.

JOSEPH MAYER, OF SEATTLE, WASHINGTON.

DESIGN FOR A HANDLE OF SPOONS OR SIMILAR ARTICLES.

No. 39,637.

Specification for Design.

Patented Oct. 27, 1908.

Application filed August 17, 1908. Serial No. 449,003. Term of patent 3½ years.

To all whom it may concern:

Be it known that I, JOSEPH MAYER, a citizen of the United States, residing at Seattle, county of King, State of Washington, have invented a new, original, and ornamental Design for the Handle of a Spoon or Similar Article, of which the following is a specification, reference being had to the accompanying drawing, forming part thereof.

Figure 1 is the obverse view of the handle of the spoon, or similar article, showing the design, and Fig. 2 is the reverse view thereof.

I claim:

The ornamental design for the handle of a spoon, or similar article, as shown.

JOSEPH MAYER.
